LEAD CONNECTOR AND CAP

John H. Thornberry, Whitefish Bay, Wis., assignor
to Milwaukee Gas Specialty Company, Milwau-
kee, Wis., a corporation of Wisconsin

Application March 31, 1947, Serial No. 738,455

1 Claim. (Cl. 173—328)

1

This invention relates, in general, to electric switches and has particular relation to an improved form of combined lead connector and cap.

While the particular device which I shall describe hereinafter in connection with the drawing is a combined electric switch and quick detachable terminal connector for use with a thermoelectric safety shutoff device and its thermocouple leads, it is to be understood that the invention is not limited to such use but may be employed for all similar purposes as suitable or desired.

The combined electric switch and quick detachable terminal connector of the present invention may be characterized as an improvement on the electric switch and terminal connector disclosed and claimed in prior patent of Stanley S. Guelson No. 2,318,775, granted May 11, 1943.

One of the main objects of the present invention is to provide in a switch of the class described quick detachable terminal connector means adapted to provide a quick detachable terminal connection between the lead conductors and the thermoelectric safety shutoff or other device, and a new form of switch at the quick detachable terminal connection for opening or disengaging and closing or completing the circuit between the lead conductors and the connected device.

Another object of the invention is to provide a new form of electric switch and terminal connector which is operable to provide an effective manual release feature whereby the safety shutoff valve of the thermoelectric shutoff device may be closed manually by the simple expedient of jacking the terminal of the thermocouple attaching nut out of contact with the cooperating terminal connected to the coil of the electromagnet of the thermoelectric shutoff device.

Another object of the invention is to provide a new form of electric switch and terminal connector having various features of novelty and advantages, and which is particularly characterized by its simplicity in construction, its relatively few parts, its economy in manufacture and its effectiveness in use.

Another object of the invention is to provide an electric switch and terminal connector comprising a cap having internal splined or keyed engagement with the attaching nut and held against axial movement relative thereto, which cap encloses the terminal means and is adapted to be grasped with the hand and turned to screw the nut into and from a cooperating bushing to move the terminal of the attaching nut into and

2

out of contact with its cooperating terminal member.

Further objects and advantages of the invention will be apparent from the following detailed description, taken in connection with the accompanying drawing in which:

Figure 1 is a longitudinal axial sectional view through a safety shutoff device embodying the electric switch and quick detachable terminal connector of the present invention;

Figure 2 is an enlarged sectional view showing the terminal of the attaching nut out of contact with the cooperating terminal member;

Figure 3 is a fragmentary sectional view taken on the line 3—3 of Figure 1; and

Figure 4 is a fragmentary and more or less diagrammatic view showing the safety shutoff device shown in Figure 1 in a fuel supply system for a main burner and a pilot burner.

Referring to the drawing, the burner shown at 10 in Figure 4 is any suitable or preferred main burner, for example, for an oven, room, or space heater, water heater, floor furnace, oven burner, top burner or any other burner.

The main burner 10 is supplied with fuel by a pipe 11 which is connected to the burner through the interior of the safety shutoff valve designated in its entirety at 12. Where the burner 10 is a gas burner, the fuel supply pipe 11 is preferably connected to the burner through a suitable air and gas admixture chamber and fuel delivery nozzle at the burner (not shown), as well understood in the art.

Figure 4 shows a pilot burner 13 in juxtaposition to the main burner 10. The pilot burner 13 is adapted to provide a pilot light 14 for lighting the main burner. A fuel supply pipe 15, connected, for example, to the safety shutoff valve 12 or to the fuel supply line otherwise as desired, supplies gaseous fuel to the pilot burner 13.

The safety shutoff valve 12 is, in general, of the type shown in the prior patent of Clarence Wantz No. 2,307,871, patented January 12, 1943. It comprises a valve body 16 having an inlet 17 and an outlet 18. Contiguous sections of the pipe 11 are connected to the inlet 17 and outlet 18. The inlet 17 opens into an inlet chamber 19, and the outlet 18 opens from an outlet chamber 20. A port or passage 21 provides for communication between the inlet chamber 19 and the outlet chamber 20. Valve seats 22 and 23 are provided on the partition 23' through which the port 21 opens; one of these valve seats 22 surrounding one end of the port 21, and the other

valve seat 23 surrounding the other end of this port.

The safety shutoff valve or flow controlling member 24 is fixed, for example, by a pin 25 upon the inner end of the valve stem 26, preferably for some relative movement thereon so as to have self-accommodating seating engagement with the cooperating valve seat 22. The valve member 24 is preferably provided with a valve gasket or yielding valve facing 27 secured in place by a screw 28, or in any other suitable manner, and adapted to engage the valve seat 22 when the safety shutoff valve is closed.

The valve stem 26 extends outwardly for reciprocatory movement through an opening in the inner end of a magnet and armature housing 29. The armature 30 is secured to the outer end of the valve stem 26 preferably sufficiently loosely to permit self-accommodation of the armature to the pole ends of the magnet frame 31. The stem 26 is disposed generally concentrically of the housing 29, and the armature and magnet frame are disposed within this housing. The housing 29 fits telescopically in a cap or hood 32, which, for example, is screwed at 33 into the valve body 16 preferably with a sealing gasket 34 therebetween. A valve spring seating member 35 abuts the inner end of the housing 29, and packing is preferably interposed therebetween at 36. The valve spring 37 is in the form of a coiled compression spring interposed between the safety shutoff valve member 24 and the seating member 35.

The magnet frame 31 is secured to a terminal bushing 38. The shank of the bushing 38 extends through an opening in the outer end of the cap 32 and is externally threaded for threaded engagement with a nut 39 by means of which the bushing 38 is clamped to the outer end of the cap 32. A sealing gasket 40 is preferably interposed between the headed inner end of the bushing 38 and the outer end of the cap 32. The outer end of the housing 29 is peened, for example, at 41 over the flanged or headed inner end of the bushing 38.

In the illustrated embodiment of the invention a thermocouple, indicated at 42, is positioned so that the hot junction 43 thereof will be heated by the pilot flame 14 as long as the pilot flame is burning. The thermocouple and leads therefor selected for illustration may be similar to the thermocouple and leads more fully disclosed in Oscar J. Leins Patent No. 2,126,564, patented August 9, 1938, or the thermocouple and leads may be of any other suitable or preferred form.

For the purpose of the present description, suffice it to state that the particular thermocouple selected for illustration comprises an outer tubular metallic thermocouple element and an inner metallic thermocouple element of different thermoelectric characteristics. The inner thermocouple element is joined at one end to the outer end of the outer thermocouple element to form the thermojunction 43 which is placed in position to be heated by the pilot flame 14. An inner lead conductor 44 is joined to the inner thermocouple element to form an internal thermojunction, and an outer tubular lead conductor 45 surrounds the inner lead conductor and is connected to the outer thermocouple element, for example, through a sleeve 46 to form a third thermojunction. The inner lead conductor 44 is insulated from the outer lead conductor 45, for example, by a wrapping of insulation 47 on the inner lead conductor.

A quick detachable or removable connection and manual release feature are provided between the electromagnet of the safety shutoff device and the ends of the leads 44 and 45 opposite the ends which are connected to the thermocouple elements. To this end the inner lead conductor 44 is provided with a connector or terminal cone 50 as shown in Figure 1. The cone 50 seats in a correspondingly recessed outer end of a terminal tip 51 and is clamped in contact therewith by a connector sleeve 52. The adjacent end of the outer tubular lead conductor 45 is connected in circuit with one side of the coil 53 through the connector sleeve 52 and bushing 38. The other side of the coil 53 is connected to the terminal tip 51, the parts being suitably insulated as shown. The coil 53 is wound around the legs of the magnet frame 31 which, with the coil 53, constitutes the electromagnet of the device shown in the drawings.

The cap 54 has an annular flange 55 which surrounds the terminal connection and the adjacent end of the cap 32. The outer end of the cap 54 is of reduced diameter at 56 and has internal splined or keyed engagement at 57 with the outer end of the connector sleeve 52 which is screwed into the outer end of the bushing 38. The end of the outer tubular lead conductor 45 is peened over the inner end of the connector sleeve 52 and insulated from the connector cone 50 by insulation at 58. The outer end of the reduced diameter part 56 of the cap 54 has an end wall or flange 59 provided with an axial opening through which the lead conductors extend. The end wall or flange 59 is fixed between the outer end of the connector sleeve 52 and a collar or abutment member 60 fixed on the tubular lead conductor.

For the purpose of resetting the valve 24 to open position and the armature 30 to attracted position, reset stem 65 is mounted for reciprocatory movement axially in a closure member 66. The member 66 is screwed into an opening 67 extending from the interior of the valve body 16 in alignment with the port 21 and valve 24. A reset button 68 is secured to the outer end of the stem 65, for example, by a pin 69. The button 68 has sliding movement in an opening 70 in the member 66.

The inner end of the stem 65 is headed and has a valve or annular rib 71 thereon which cooperates with a leather or other suitable washer 72 to seal the valve body against leakage along the reset stem 65 when the stem is in retracted position. The valve 71 and washer 72 are shown as a precaution in the event the bellows or diaphragm, to be presently described, is ruptured. In actual practice the valve 71 and washer 72 may be omitted, and the device thereby further simplified.

The flexible bellows or bellows-like or diaphragm member 75 is formed of rubber, rubber-like or other suitable material. The bellows 75 is clamped peripherally at 76 between the valve body 16 and the closure member 66 and forms an impervious covering over the inner end of the closure member 66 and the inner end of the reset stem 65, thus sealing the valve body against leakage adjacent to the closure member 66 and the stem 65. The flexible bellows 75 is shown of reduced diameter at its inner end at 77 to enter the port 21, as shown in Figure 1 when the reset stem 65 is moved inwardly to resetting position. In resetting position of the stem 65, the enlarged diameter outer portion of the bel-

lows 75 cooperates or seats annularly on the valve seat 23, thus shutting off the supply of fuel to the main burner during the resetting operation. The reduced diameter and enlarged diameter portions of the bellows 75 may be of corrugated form as shown in the drawings, or of other suitable form.

In the illustrated embodiment of the invention the pipe 15 for supplying fuel to the pilot burner 13 is connected through a port 78 with the interior of the valve body 16 between the valve seats 22 and 23. The pilot burner 13 thus receives fuel whenever the shutoff valve 24 is open and regardless of whether the flow interrupter valve formed by the bellows 75 is open or closed. This may, of course, vary widely in so far as the present invention is concerned.

The portion of the bellows 75 which extends over the inner end of the reset stem 65 is secured, for example, by vulcanizing to a serrated surface 79 on the inner end of the stem 65. The reset stem 65 and button 68 are moved to retracted or outwardly projecting position following a resetting operation by a coiled spring 80 which is shown encircling the stem 65 and interposed between the button 68 and an internal annular flange or abutment 81 on the closure member 66.

The annular and outwardly directed surface 82 formed on the cap 54 between the reduced and enlarged diameter portions thereof may be provided with "on" and "off" markings (not shown) and with arrows showing the direction in which the cap 54 should be turned to open and close the thermoelectric circuit between the thermocouple and the electromagnet. By turning the cap 54 to "on" position in the direction of the arrow adjacent to the "on" marking, the connector sleeve 52 is screwed inwardly into the bushing 38 to engage the cone 50 with the terminal tip 51, thus completing the circuit between the thermocouple and the electromagnet. By turning the cap 54 to "off" position in the direction of the arrow adjacent to the "off" marking, the connector sleeve 52 is screwed outwardly from the bushing 38, thus separating the cone 50 from the terminal tip 51 and opening the circuit between the thermocouple and the electromagnet. This provides an effective manual release feature whereby the shutoff valve 24 may be closed by jacking the terminal cone 50 out of contact with the socketed end of the terminal tip 51.

In general, the operation of the device is similar to the operation described in the prior patents previously mentioned and, being well understood in the art, will not be described in detail. Suffice it to state that the flexible bellows 75 constitutes a flow interrupter valve which is adapted to be stretched by the resetting operation of the reset stem 65 into engagement with the cooperating valve seat 23 to shut off the flow of fuel to the burner during the resetting operation. With the bellows arranged as shown and described it also performs the additional function of sealing the device against leakage of fuel from the valve body 16 adjacent to the reset means. The cap 54, with its keyed or splined engagement with the connector sleeve 52 and its mounting against axial movement relative to the sleeve 52 provides a manual release feature whereby the shutoff

valve 24 may be closed manually by merely turning the cap 54, which thereby jacks the terminal cone 50 out of and into contact with the socketed end of the terminal tip 51.

5 The invention is not limited to use with a valve type safety shutoff device as shown in the drawing but may be employed with switch type shutoff devices; also on automatic valves such as those employing a thermopile or other type of thermo- 10 electric generator and elsewhere as suitable and desired.

The embodiments of the invention shown in the drawings, therefore, are for illustrative purposes only, and it is to be expressly understood that the 15 drawing and the accompanying specification are not to be construed as a definition of the limits or scope of the invention, reference being had to the appended claim for that purpose.

I claim:

20 In a device of the class described, in combination, a terminal bushing having a threaded part, a first terminal member fixed in said bushing and insulated electrically therefrom, a connector member having threaded engagement with the 25 threaded part of said bushing and adapted to be screwed from and toward said bushing, a cap having an end wall in juxtaposition to the adjacent end of said connector member and fixed internally against turning movement relative to said connector member whereby said connector member is turned by turning of said cap, conductor means comprising an outer tubular lead conductor extending axially through the end wall of said cap and axially through said connector 30 member, an inner lead conductor extending through said tubular lead conductor and insulated therefrom, a second terminal member fixed on the inner end of said inner conductor beyond the inner end of said outer tubular conductor 35 and in juxtaposition to said first terminal member, insulation between said second terminal member and the inner end of said connector member and abutting the inner end of said connector member, and an abutment member fixed 40 externally on said outer tubular conductor with said cap, connector member and insulation held against relative longitudinal displacement between said abutment member and said second terminal member whereby turning of said cap screws 45 said connector member toward and from said bushing and said second terminal member into and out of contact with said first terminal member.

JOHN H. THORNBERRY.
